UNITED STATES PATENT OFFICE.

OTTO W. GREENE, OF ELYRIA, OHIO, ASSIGNOR TO THE INTERNATIONAL PULP STONE COMPANY, OF ELYRIA, OHIO, A CORPORATION OF OHIO.

GRINDER FOR REDUCING WOOD OR OTHER FIBER TO PULP.

Application filed March 15, 1923. Serial No. 325,251.

To all whom it may concern:

Be it known that I, OTTO W. GREENE, a citizen of the United States, residing at Elyria, in the county of Lorain, State of Ohio, have invented a certain new and useful Improvement in Grinders for Reducing Wood or Other Fiber to Pulp, of which the following is a specification, reference being had therein to the accompanying drawings.

This invention relates to apparatus for making paper pulp and relates more particularly to grinders for cutting the pulp wood into pulp.

Practically all the pulp grinders used today are made of a natural stone. Many efforts have been made to use grinders made of emery, corundum and the like but none have been successful and so far as I am aware none are now in use.

It is well known that certain natural stones are well adapted and preferable for use in making grinders to cut the wood into pulp but hitherto, so far as I am aware, the natural stone grinders used in successfully grinding wood pulp have always been made of a single stone. The natural stone is relatively soft, crumbly and fragile and if once chipped between the ends, the stone is useless or greatly reduced in efficiency unless it be turned away by special means beyond the depth of the chip. Owing to the fact that the large stones are best adapted for the purpose of grinding pulp and owing to the fact that fissures or crevices frequently occur in natural stone which would destroy or greatly impair the stone's use as a grinder, large natural stones are relatively hard to find and expensive to produce. Many efforts have been made to build up these grinders from sections of natural stone but so far as I am aware all former efforts have failed for one reason or another. The stones have crumbled or chipped away at the joints or have slipped in the turning so that an uneven surface has resulted which has caused uneven grinding so that the stone was useless.

One of the objects of this invention is to produce a grinder, built from sections of stone, which grinder will not chip, crumble or wear unevenly but which, on the contrary, will wear throughout its lifetime in substantially the same manner as a single natural stone.

Another object of this invention is to provide means for connecting the sections of stones together with sufficient rigidity and at the same time without exposing the attaching means unduly to the grinding surface and without shortening the life of the stone.

This and other objects of my invention will be apparent from the particular description of the embodiment of the invention illustrated in the drawing and described in this specification.

In the drawings Fig. 1 is a longitudinal, medial section of the assembled sectional grinder, a portion only of the shaft being shown, and means for securing the sections together being shown in elevation. Figure 2 is an end elevation of the sections comprising the grinder; and Figure 3 is a side elevation of the inner face of one of the sections.

In the drawings 10 and 11 represent two disks or sections of stone which are secured together to form the body of a grinder which is used in grinding logs of wood or similar fibrous material into pulp, for use in paper making and other similar purposes. I preferably have shown a grinder formed of two sections, but if desired, a larger number of sections could be used to form a grinder of the same or different widths.

The adjacent or contiguous surfaces of the stones are parallel and slightly inclined from the normal to the axle axis, which is horizontal in Fig. 1, or to the axle of the grinder. In the embodiment shown the face is at an angle of 8° to a plane normal to the axle axis and this is the preferred inclination.

The inner portion of the contiguous faces of the grinder sections may be cut away at 14, to provide a wider seam theretwix than is present at the outer grinding portion of the contiguous faces. The outer grinding portion 15 of the contiguous faces are preferably parallel, exposing a minimum width of seam as the grinding surfaces wear down.

Aligned openings 16 extend longitudinally through the sections of the grinder and terminate in pockets 17 formed at the outer walls thereof. In the embodiment shown pockets 18 are formed in the inner contiguous walls of the sections, and as shown,

provide an enlargement of the openings 16 across the seam. These pockets 18 may be formed separately from the openings 16 and the bolts, if desired, and may be used as 5 the sole longitudinal securing means or can be used in combination with the aligned openings.

Bolts 19 extend through the openings and the pockets, and the ends thereof are 10 threaded to receive nuts 20 which, when screwed upon the bolts, lie within the pockets 17 and draw the sections together. The openings 16 are of sufficient diameter to receive the bolts and allow them to be entirely 15 embedded in a plastic binder 21, such as cement, when united together. It is preferable that sufficient cement be inserted to fill the inner and outer pockets and the openings around the bolts. A similar binder 20 22 is placed between the contiguous inner faces of the sections filling the seam therebetween.

The annular cement filled seam, between the contiguous faces of the stone sections, 25 presents a surface which will remain flush with the stone sections as they wear down, regardless of whether or not the cement is harder or softer than the stone. The cement within the openings 16 and the pockets 18 provide rigid retaining members 30 which will prevent the sections from separating when in operation.

If desired, the cement in the bolt holes can be eliminated entirely and the bolts 35 alone relied upon, in which case a strong serviceable connection is maintained. The pockets in the aligned faces of the sections, provide a dowel joint for the sections when filled with cement. The angular seam being 40 wider at the inner portion, also allows the outer surface to be closely fitted in order to leave as little cement as possible in the portion of the stone which is used for grinding.

45 When in operation the assembled grinder is secured upon a rotatable shaft 24, which extends through an axial opening 23 in the sections, and the peripheral surfaces thereof provide an unbroken grinding face.

50 Various changes in the details of construction can be made without departing from the spirit of the invention and the scope of the appended claims.

What I claim is:

55 1. In a grinder for wood pulp, the combination of a plurality of substantially cylindrical sections made of natural stone, an axle upon which said stones are mounted, contiguous faces of said stones being parallel to each other and slightly inclined from 60 a plane perpendicular to the long axis of

the axle, and means for rigidly binding said stones together at their contiguous inclined faces.

2. In a grinder for wood pulp, the combination of a plurality of substantially cylindrical sections made of natural stone, an axle upon which said sections are mounted, the said sections being of the same diameter and having contiguous faces parallel and 65 each slightly inclined from a plane perpendicular to the long axis of the axle, and means for rigidly binding said sections of natural stone together including bolts or the like offset from said axle and remote 70 from the grinding faces of the stones.

3. In a grinder for wood pulp, the combination of a pair of substantially cylindrical sections of natural stone, pierced at the center for an axle, an axle upon which said 80 stones are mounted, said stones having parallel adjacent surfaces inclined to the long axis of the axle, and means to rigidly connect said stones together on said axle.

4. In a grinder for wood pulp, the combination of a plurality of substantially cylindrical parts composed of sand stone pierced at the center for an axle, an axle upon which said stones are mounted, adjacent surfaces of said stones being parallel and inclined from the normal to the long 90 axis of said axle, and means to rigidly connect said stones together including bolts offset from said axle, and cementing material between the adjacent inclined surfaces of 95 said stones.

5. In a grinder for wood pulp, the combination of a plurality of substantially cylindrical sections of sand stone, adjacent 100 surfaces of said stones being parallel and being inclined from the normal to the main axis of the sections, and means for rigidly connecting said stones together.

6. In a grinder for wood pulp, the combination of a plurality of substantially cylindrical stones of the same diameter for mounting on an axle, contiguous surfaces of said stones being parallel and slightly inclined from the normal to the axle axis of the stones, and means for connecting said 110 stones rigidly together including a cementing material and a plurality of bolts or the like.

7. In a grinder for wood pulp the combination of a plurality of substantially cylindrical stones having adjacent parallel surfaces inclined about eight degrees from the normal to the axle axis and means for rigidly binding said stones together.

In testimony whereof, I hereunto affix my 120 signature.

OTTO W. GREENE.
